UNITED STATES PATENT OFFICE.

SAMUEL SUEKOFF, OF CHICAGO, ILLINOIS.

CUSHION-COVER CONSTRUCTION.

Application filed July 24, 1925. Serial No. 45,735.

To all whom it may concern:

Be it known that I, SAMUEL SUEKOFF, a citizen of the United States of America, and a resident of Chicago, in the county of Cook 5 and State of Illinois, have invented a certain new and useful Improvement in Cushion-Cover Constructions, of which the following is a specification.

This invention relates to improvements in 10 cushion construction, and more particularly to an efficient and economical method of fabricating and assembling cushion covers adapted for use with resilient filling units such as springs or cushioning material.

15 As commonly made, a cushion cover consists of pieces of fabric, usually burlap, cut and sewn together not only to form the bottom, top and side walls, but a series of individual cells or pockets within the outer 20 walls, and adapted to contain the resilient material units. The problem of making cushion covers is not merely one of structure, but it is one of the method of preparing the material for sewing, and then sewing the 25 pieces together, so that the cushion can be loaded with resilient material with the least amount of time and labor.

In a companion application filed by me on 30 the 18th day of July, 1925, Serial No 44,416, I have shown and described an improved construction of cushion cover and method of manufacturing the same, including the use of so-called "combs" or integral strips 35 of material used for forming certain side walls of individual compartments. In the present invention I provide an improved construction wherein the combs themselves may be economically manufactured and incorporated in the completed cover with 40 greater facility and less operating cost.

The principal object of the present invention is therefore to provide a method of further reducing the labor cost of cushion construction, attention being called to the 45 fact that in the present highly competitive state of the cushion industry, an unprofitable business may become profitable by an apparently inconsequential saving in the item of labor or material costs. Thus, the 50 elimination in one step of the manufacturing process, or the completion of two steps in a single operation, or a more efficient treatment of the material in preparation for assembling, would be important to the manufacturer in meeting competition.

Of such a nature is the present invention, and its applicability to the art will be better appreciated as the process is disclosed with the aid of the accompanying drawings, in which:

60 Figure 1 is a perspective view showing a portion of the material forming one of the covers, said material being marked off for subsequent sewing of partition strips along predetermined lines;

65 Figure 2 is a similar view of the piece shown in Figure 1 but illustrating the arrangement of two sets of combs and a partition strip as applied thereto to form a base;

70 Figure 3 is a detailed view in vertical section of the completely assembled cushion taken on line 3—3 of Figure 2;

75 Figure 4 is a view similar to Figure 3, but taken at right angles thereto;

Figure 5 is a detailed view illustrating the 80 method of manufacturing the combs before sewing into the structure.

Regarding first the structure of the cushion as a whole, a portion of which is shown in Figures 3 and 4, the same consists 85 of top and bottom pieces 1 and 2 of suitable fabric, such as burlap, sewn together at the edges in a seam 3 extending around the cushion between the top and bottom thereof, the marginal portions of these pieces 90 forming a boxing or end and side walls of the cushion.

Within the outer covering formed by the pieces 1 and 2 are a series of continuous 95 partition strips 4 extending the full length (or width) of the cushion with the longitudinal edges sewn to the top and bottom cover pieces. These partition strips are parallel with each other and divide the interior space of the cushion into a plurality of full length compartments.

In connection with the compartments formed between the partition strips 4 and the outer of said strips and the parallel end (or side walls of the cover) are provided 100 a plurality of division walls 5 which divide the cushion into a plurality of smaller compartments or cells. Each set of aligned walls 5 is made from a single comb or strip of material, indicated generally by numeral 7, 105 as shown in Figure 2. The various steps taken in constructing the complete cushion cover will now be described.

The first step in the process of manufacture is to provide a pair of similar top and 110

bottom pieces 1 and 2, having sewing lines 10—10 arranged at right angles to each other to outline the size of the compartments or cells of the completed cushion. I 5 also provide a plurality of combs 7, each consisting of a strip cut from a single piece of material and having a series of notches or cuts 5^b formed therein and extending almost to the base 7^a to form the tabs 5^a, 10 which subsequently form individual division walls 5, as will hereinafter appear. The base 7^a is of sufficient width to permit the comb to be secured to the cover 2 along a seam 12 which follows a sewing line 10 15 along one dimension of the cover. A preferred method of manufacturing the combs 7 is shown in Figure 5, in which the single strip of material 8 is provided, being of a width substantially equal to the height of 20 one set of tabs 5^a plus the height of two bases 7^a. This strip is marked with two rows of sewing lines 12—12 parallel to and adjacent each margin thereof and a second row of sewing lines 5^c parallel to and spaced 25 inwardly from the first named pair of sewing lines 12—12. The strip is then cut along transverse lines 8^a and longitudinal lines 8^b so as to form two sets of combs in which the width of each of the tabs 5^a is the 30 same as the notches 5^b. The cutting operation may be carried out in any suitable manner, as for instance by rotary cutting machines of a type well-known in the art, which may be readily adapted for the purpose. The continuous strips formed into combs, as described, are then cut into suitable lengths and secured to the cover 2 along sewing lines 12—12, previously marked on the base 7^a, close to the bottom 35 margin of the notches 5^b now formed therein. An entire series of strips or combs 7 are sewn in parallel relation along adjacent sewing lines 10 on the bottom cover piece 2 and thereafter a plurality of partition 40 strips 4 are also secured to the cover 2 along seams 4^a, these seams following transverse sewing lines 10 at right angles to the combs 7 and passing through the center of aligned notches 5^b—5^b, as indicated in Figure 2. 45 The partition strips 4, when in secured position, are substantially as high as the upper or free edges of tabs 5^a. With the cover 2, combs 7 and strips 4 all secured together, as described, top cover 1 is then applied 50 thereto. The preferred method of applying and sewing the parts together is as follows: Starting along one edge of the cushion, 55 parallel with the partition strips 4, the cells or compartments are completed progressively in rows toward the opposite edge of the cushion, substantially in the following manner: The first row of tabs 5^a between the first partition strip 4 and the cushion edge are sewn to the top cover 1 along seam 60 lines 5^c it being understood that said cover

1 is marked off by sewing lines 10—10 to serve as a guide for these sewing operations. The free upper edge of the first partition 4 is then sewn to the upper piece 1 along the seam 4^b, as shown in Figure 3, this sewing 70 operation being continuous throughout the entire length of the partition 4 to complete the first row of compartments between the first partition 4 and the adjacent end wall. The assembling operation is then continued 75 by sewing the second row of tabs 5^a adjacent the first partition strip to the top piece 1 and then the next or second partition strip is sewn to the top cover 1 to complete the second row of compartments. This operation is repeated until all the compartments are formed. One or more of the side and end walls may be closed or boxed along 80 seams 3 at any time in the process, although of course the cushion is not finally closed or boxed along all sides until the individual compartments are loaded with suitable resilient material, as will hereinafter be described. It will be observed that in the preferred form shown the strips 5 are positioned centrally between partition strips 4 and are only one-half the width of each compartment. I have found, however, that partition strips of such width are fully capable of performing the function of division walls 90 for resilient material, especially in cases where the cushion is loaded with individual springs.

One of the principal advantages of the construction above described is the provision 100 of the combs 7 and partitions 4 in such a manner that they may each be connected to the cover 2 in a single sewing operation, while the method of assembling the upper cover to combs 7 and partitions 4 may be 105 readily accomplished with the seams open and exposed at all times for application to the stitching machine, and thus eliminating the danger of "blocking" or making seams 110 so difficult of access by the stitching machine as to require special handling and extra labor during assembly. A further advantage is the saving in labor and material in the formation of the combs 7 from strips 8 in the manner described with the sewing lines 12 and 5^c marked on the strip 8 before cutting so as to insure uniform height 115 of the cushion when finally completed. A still further advantage is that the sides of the strips 5 are loose—that is to say they 120 are not joined along their side margins to partitions 4 but are spaced considerably therefrom, so as to promote ready ventilation of the cushion, and also to permit a flexibility that is essential to rapid and convenient loading of the cushion with resilient material.

The cushion described is particularly adapted for use with resilient springs comprising helical coils of wire, which springs 130

may be inserted through the loose side of each row of compartments. As a preferred method of loading the cushion with springs, an implement known as a loading tool is used in which a number of springs equivalent to the number constituting a single row, are held flatly compressed within the tool. The tool is then inserted into the open end of the cushion and along one side of each longitudinal compartment formed between successive partition strips 4, the tool being held so that the flattened springs pass through the openings between the partition strips and the adjacent edges of the tabs.

It will be understood, however, that a cushion cover constructed in accordance with my invention may also be loaded with other resilient cushioning means.

As before explained, the process of assembling the cushion cover from corresponding combs and transverse partitions 4 results in a marked saving of time, labor and material in the manufacture of the cover, eliminating the sewing of a multitude of short seams, each of which may be a separate sewing operation.

I claim:

1. A cushion cover construction compris-

ing top and bottom cover pieces, a plurality of parallelly disposed combs each consisting of a single piece of material initially sewn along one edge to one of said cover pieces and provided with spaced cuts extending from the free outer edge substantially down to said sewn edge, a plurality of partition strips arranged transversely of said combs and sewn to said cover piece along lines passing through aligned cut portions of said combs, said combs and partition strips being substantially of equal height and each sewn along its outer edge directly to the opposite cover to form a continuous strip connecting said covers together.

2. In a cushion cover construction, a top and bottom cover piece, and means connecting said cover pieces together to form cells including a plurality of combs arranged in parallel lines, said combs each consisting of a single piece of material having a base and a plurality of tabs extending therefrom, said tabs being separated from each other a distance substantially equal to their own width.

Signed at Chicago this 17th day of July 1925.

SAMUEL SUEKOFF.
